UNITED STATES PATENT OFFICE.

JOHN M. BEERE, OF ST. PAUL, MINNESOTA.

SKIRT AND GARMENT MARKING DEVICE.

No 851,642.

Specification of Letters Patent.

Patented April 30, 1907.

Application filed November 2, 1905. Serial No. 285,512.

To all whom it may concern:

Be it known that I, JOHN M. BEERE, a subject of the King of Great Britain, residing at St. Paul, in the county of Ramsey and State of Minnesota, have invented certain new and useful Improvements in Skirt and Garment Marking Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to means for marking upon garments, especially skirts, the distance from the floor at which it is desired to shorten them when too long.

The device is designed for use by those fitting ready-made skirts onto ladies, but is also useful for dressmakers in general, and even tailors or sellers of men's trousers may use it in marking the height from the floor the trousers are to be fitted.

In the accompanying drawing Figure 1 is a front elevation of my marking device as applied to a portion of a garment shown in dotted lines. Fig. 2 is a side elevation of Fig. 1, with fingers of a human hand added. Fig. 3 is a modification of Fig. 2, showing the entire device made from sheet metal, while in Figs. 1 and 2 the main parts are supposed to be made of wood.

Referring to the drawing by letters of reference, A is a foot or base plate upon which a broad standard B is fixed. In front of said standard is secured to the base the lower end of a vertically disposed scale plate C, which in one edge is graduated with horizontal notches D, and numbers adjacent thereto, as indicated in Fig. 1 by 1, $1\frac{1}{2}$, 2, $2\frac{1}{2}$, 3, &c., representing inches and fractions of inches, or such other measure as may be customary to use. The scale starts from the floor line E and increases upward.

The scale C is hinged or pivoted at F to the base and provided with a stop G, which when resting on the base holds the scale in the inclined position shown in dotted lines in Fig. 2, so that the skirt H may be easily dropped down between the standard and the scale. The scale is also springy, so that it may be sprung as at I in Fig. 2 against the surface of garments of various thicknesses at the lower edge. In Fig. 3 is shown that

by making the scale of thin spring metal it may be so much sprung at I² that it will need no pivot, but can be riveted at F² to the base. In Fig. 3 is also shown that the base A, 60 standard B, and even the finger catch J may be formed integral from a single piece of sheet metal, while in Figs. 1 and 2 the catch J is a peg secured into the base.

In using the device the tailor, dressmaker 65 or fitter sets the device on the floor, puts the skirt or other garment on the person it is to be fitted on, drops the lower edge of the garment down between the standard and the scale, then places one finger K back of the 70 catch J, so as to hold the device firmly to the floor and prevent its moving away for the pressure of the thumb L against the scale C, by which the latter is held against the garment and holds it smooth against the standard while the operator places his marking chalk in one of the notches D and makes a horizontal mark, about like M in Fig. 1, at the desired height from the floor; the scale is then released and the device moved along the 75 floor to other points of the garment, where further marks are made, either at the same height as the first mark, or changing gradually upward or downward as may be desired. The garment is then removed, trimmed and 80 sewed to the marks thus made. If the garment is too long to hang down between the standard and the scale then its lower edge is simply turned in and upward while the marking is being done. When the scale is pivoted 85 to the base a slight outward tilting of the device will throw the scale away from the standard, and when the scale is not pivoted, as in Fig. 3, it will spring away from the standard as soon as released from the thumb. 90

It will be readily understood that this device is very handy and convenient, especially as compared to the old methods of marking by the insertion of a lot of pins, or by handling simultaneously a tape-line, the 100 chalk and a garment hanging free to swing away in any direction from the slightest touch, while this device steadies and holds the garment firmly, provides its own measure or scale, furnishes guiding means for the 105 chalk and the standard as a table supporting the garment against the chalk.

Having thus described my invention, its use and advantages, what I claim as new and desire to secure by Letters Patent, is:—

1. A garment marking device comprising a foot piece with a standard thereon and a

scale secured on the base and adapted to be pressed toward the standard, said base having a finger catch by which to hold it against the pressure exerted upon the scale, substantially as and for the purpose set forth.

2. A garment marking device comprising a foot or base, a standard projecting upwardly therefrom, and a scale secured to the base near the standard and adapted to swing to and from the same, said base and standard being formed integral of a single piece of sheet metal.

3. A garment marking device comprising a base or foot piece, a standard extending upward from the same, a graduated scale mounted on the base and adapted to swing to and from the standard, and be pressed against the latter, and a finger catch on said

base; said base, standard and catch being made integral from a single piece of sheet metal.

4. A garment marking device comprising a base adapted to rest upon the floor, a standard fixed thereto, a vertically disposed graduated scale secured to the base near the standard and adapted to be forced against a garment placed between it and the standard, said scale being springy near its lower end, for the purposes set forth.

In testimony whereof I affix my signature, in presence of two witnesses.

JOHN M. BEERE.
